US00D667420S

(12) **United States Design Patent** (10) **Patent No.:** **US D667,420 S**
Kriese et al. (45) **Date of Patent:** **** Sep. 18, 2012**

(54) **DISPLAY SCREEN WITH GRAPHICAL USER INTERFACE**

(75) Inventors: **Jason P. Kriese**, Seattle, WA (US); **J. Craig Hally**, Sammamish, WA (US)

(73) Assignee: **Microsoft Corporation**, Redmond, WA (US)

(**) Term: **14 Years**

(21) Appl. No.: **29/401,484**

(22) Filed: **Sep. 12, 2011**

(51) **LOC (9) CL. 32-00**

(52) **U.S. CL. D14/487**

(58) **Field of Classification Search** D14/485–495; 715/722, 723, 772

See application file for complete search history.

(57) **CLAIM**

The ornamental design for a display screen with graphical user interface, as shown and described.

DESCRIPTION

FIG. 1 is a front view of a display screen with graphical user interface showing the new design; and,

FIG. 2 is a front view of a display screen with graphical user interface showing the design from FIG. 1 with additional disclaimed environment.

The broken line showings of the remainder of the graphical user interface and of the display screen are for environmental purposes only and form no part of the claimed design.

1 Claim, 2 Drawing Sheets

FIG. 1

FIG. 2
